2,070,857

LIGHT EQUIPPED VANITY CASE

Myron J. Davis, Detroit, Mich.

Application September 4, 1934, Serial No. 742,566
Renewed August 17, 1936

1 Claim. (Cl. 340—6.45)

This invention relates to vanity cases such as are used by women for carrying and to assist in the application of cosmetics, and relates also to flash-light constructions aiming particularly to provide a structure combining a flash-light with such a vanity case in a novel manner incorporating many advantages, among which may be mentioned the arrangement of the light in such manner as to both assist in the use of the case and its contents, and enable use of the device as a simple flash-light, whether the case is open or closed.

Another important object of the invention is the provision of a device of this nature which is of extremely simple and inexpensive construction, and the parts whereof are so arranged as to provide a case of minimum thickness, those which would tend to render the case of undesirable proportions being disposed in a novel manner calculated to greatly minimize this tendency.

Other objects include the improvement of various elements of construction of cases of the type indicated, as well as of flash-light constructions and switching means therefor, in manners making for compactness and inexpensiveness of construction, attractiveness of appearance and ease of use.

Other objects and advantages will be apparent from the following description, wherein reference is made to the accompanying drawing illustrating a preferred embodiment of my invention, and wherein similar reference numerals designate similar parts throughout the several views.

35 In the drawing:

Figure 1 is a perspective view of a vanity case incorporating the principles of this invention, showing the same completely closed;

Figure 2 is a perspective view of the case as seen from the opposite side, showing the lid and interior compartments open and partly opened, respectively;

Figure 3 is a plan view of the top of the case, partly broken away; and

Figures 4 and 5 are sections taken substantially on the lines 4—4 and 5—5 respectively of Figure 3, and looking in the directions of the arrows.

As clearly shown in Figures 1 and 2, the case 50 10 is preferably of tapering thickness from one end to the other. Both ends may be rounded, and the thicker proportioned to accommodate one or more electric cells as 12, which may be slipped into place through an opening closable 55 by a cap, as 14. One cell is sufficient, and it is

preferably of the smallest standard variety, known on the market as the "pen cell". Within the cap may be arranged a contact spring 15 adapted to position the cell within the cylindrical compartment 16, as well as to ground the external or 5 can electrode of the cell to the case, in the well known manner. The cell compartment is formed by a tube arranged in the thicker end of the case, in which it may be retained either frictionally or by soldering or other suitable means.

10 The portion of the case adjoining the cell compartment is provided with a partition and supporting element 17 formed of a bent sheet metal member whose configuration is fully shown in Figures 2 and 5. The substantially horizontal 15 mid-portion of member 17, which is spaced a desirable distance below the hinged cover 36, carries the bulb socket 38, while adjoining such partition and occupying the major part of the remainder and thinner end of the case is a cosmetic 20 compartment in the bottom which is a box as 18, ordinarily utilized for face powder or the like, shown in Figure 5 at 19. The powder may, if desired, be retained beneath a perforated plate as 20, and a separate internal lid, as 22, may 25 be provided for such powder box, hinged to the side of the case as at 23.

A box-like depression, as 25, may also be formed in the middle portion of the lid 22, adapted to contain another cosmetic, such as face rouge or the like, designated 27, while such box portion may be closed by an additional and smaller lid 28 hinged to the lid portion 22, as at 29, and provided, if desired, with a bulging or inwardly concaved section as 30 in a central portion thereof, 35 within which depression may be arranged still another cosmetic as 32, in cake form. This receptacle is ordinarily devoted to lip rouge or the like.

40 Suitable latching means as 34—35 may be provided for yieldably retaining the lids 22—28 in closed position, while the main cover 36 is preferably hinged to the case as at 37 near the thicker end and arranged to cover both the cosmetic compartment just described and the supporting portion 17 by which the bulb socket 38 is carried. The lid 36 preferably lies flush with the adjoining surfaces of the case when closed, and carries on its inner face a mirror or mirroring portion 40, and is also apertured as at 41 to expose the flash-light bulb 42, which, as shown, is threaded into the socket 38 in the usual manner through an opening (undesignated) in the supporting portion 17.

45 50 55 A conductor in the form of a metallic strip, 55

- as 44, insulated from the case as by a fiber or cardboard insulating members shown in Figures 3 and 4 and designated 45, may be arranged to connect the end contact of the bulb 42 with the central electrode 46 of the cell, while the socket portion 38 into which the threaded shell 43 constituting the side contact of the bulb is screwed, is preferably insulated from the case, as by the insulating means best shown in Figure 4 and designated 47.
- Switching means for controlling illumination of the bulb may consist of a spring metal strip 48 connected to the case as by being riveted to the partition portion 17, in the manner best shown in Figure 3. This element constitutes its own releasing spring as well as a spring for the simple button 50 by which it is actuatable. The button is slidable in the side of the case and so arranged that when pressed the strip 48 is pushed into contact with the metal shell 38, to ground the same and so complete a circuit through and illuminate the bulb.
- It will be seen that the disposition of the parts described is such that when the lid 36 is opened the bulb faces and is properly positioned to illuminate the face of a user of the case, and so assist in the proper use of its contents, while when the case is closed the bulb is nevertheless exposed and the button 50 readily actuatable, rendering the device conveniently usable as a simple flash-light.

A cigarette lighter, the case of which is generally designated 55, may be provided in the smaller end of the container and its active portion 57 may be carried by and utilizable upon removal of the cap 56.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claim.

What I claim is:

In a device of the character described, a case having convergent sides and thicker at one end 15 than the other, a compartment for cosmetics or the like arranged in a thinner end of the container, electric lighting means carried by the case including a cell arranged in the thicker end of the case, a bulb connectible to the cell and arranged between the cell and the cosmetic compartment, said compartment and the bulb and cell being arranged in generally coplanar relation, a lid defining one of the convergent sides of the case and hinged thereto between the cell 20 and bulb, and a mirror surface carried upon the inside of said lid, said lid being apertured to expose the bulb when closed.
